DEVICE FOR POCKETING SPRINGS

Clifford F. Peterson, Belding, Mich., assignor to
 The Murray Corporation of America, Detroit,
 Mich., a corporation of Delaware

Application September 29, 1941, Serial No. 412,820

5 Claims. (Cl. 29—87.1)

The present invention relates to devices for compressing and pocketing or inserting coil springs and particularly relates to an air operated spring compressor for filling burlap strips with such springs.

One of the primary objects of the present invention is to provide improvements in devices of the type mentioned, whereby coil springs may be properly and quickly inserted in the pockets of the burlap strips.

A further object of the invention is to provide improvements in devices of the type mentioned which are adapted for use with coil springs of different dimensions and by which such coil springs are compressed and retained compressed for ready insertion in the pockets of burlap upholstery elements.

A further object of the invention is to provide improvements in devices of the type mentioned in which improved gauge or guide means is provided which engages and guides the spring during compression thereof and which is moved out of the way after compression so that the springs may be readily inserted in the pockets of burlap strips.

A further object of the invention is to provide improvements in compressors for springs which are so constructed that they are adapted to handle springs of different lengths and of different diameters.

Other objects of the invention will become apparent from the following specification, the drawings relating thereto, and from the claims hereinafter set forth.

In the drawings, in which like numerals are used to designate like parts in the several views throughout:

Figure 1 is a perspective view of a coil spring compressor and pocketing device according to the present invention;

Fig. 2 is an enlarged, fragmentary top plan view taken substantially along the line 2—2 of Fig. 1;

Fig. 3 is an enlarged, side elevational view of the structure shown in Fig. 1;

Fig. 4 is a partial, end elevational view taken in the direction of the arrow 4 of Fig. 3;

Fig. 5 is a cross-sectional view taken substantially along the line 5—5 of Fig. 4;

Fig. 6 is an end elevational view taken substantially along the line 6—6 of Fig. 5;

Fig. 7 is an enlarged, elevational view taken substantially along the line 7—7 of Fig. 4;

Fig. 8 is a diagrammatic, perspective view illustrating the spring in its compressed position and before insertion in a burlap strip;

Fig. 9 is a fragmentary, elevational view of a burlap strip having the spring initially inserted into the bottom of the pocket thereof; and

Fig. 10 is a view similar to Fig. 9 illustrating the spring after it has been turned around and expanded to fill the pocket.

According to the present invention, an apparatus is provided for compressing coil springs and for supporting such coil springs in their compressed condition while they are being inserted into the pockets of burlap strips. The apparatus includes a pair of superimposed elements between which the spring is supported above a table support. The upper of the elements is moved toward the lower element to compress the spring and to hold the spring in such compressed condition while the burlap strip is slipped over the free ends of the elements. The spring is thus deposited into the bottom of the burlap pocket, and the open end of such pocket sewed shut. The spring may then be turned around to a position longitudinally of the pocket, where it expands to fill the pocket.

Referring to the drawings for a detailed description of the apparatus, such apparatus includes a table support generally indicated at 10, which includes a frame and a top table support 12. The compressor includes a pair of superimposed arms 14 and 16, which are disposed above the table 12 so that the free ends of such arms 14 and 16 extend toward one end of the table.

The upper arm 16 is fixed adjacent one of its ends to a cross head 18. Such cross head 18 is provided with vertical openings at the sides thereof, to which the upper ends of depending rod members 20 are attached. Such rod members are slidably disposed within tubular supporting and guiding members 22 which are also disposed vertically and which extend downwardly through openings in the table 12. The members 22 are fixed to and extend through a mounting plate 24, which is secured to the table 12 by means of bolts 26. The rods 20 may be guided within the tubular members 22 by means of spaced bearing sleeves 28 which are disposed within the members 22 and fixed thereto, preferably adjacent the upper and lower ends thereof.

The upper arm 16 is adjustably connected to a vertical piston rod 28 through the cross head 18. In order to so connect the cross head 18, the rod 28 is provided with a plurality of vertically-spaced openings 30 therethrough. A spring latch 32 is secured to the cross head 18 intermediate the ends thereof and has a tapered end portion 34 which is adapted to be removably received with-

in any one of the apertures 30. The rod 28 extends through a central aperture in the cross head 18, and by sliding such cross head axially with respect to the rod 28 it will be appreciated that it may be fixed in position at any one of the plurality of apertures 30 through the cooperating action of the latch pin 32. By so adjustably fixing the position of the upper arm 16 with respect to the rod 28, it will be appreciated that the compressor may be adjusted to accommodate coil 10 springs of different lengths.

The lower arm 14 is fixed to the top surface of the plate 24 by means of suitable bolts so that it assumes a fixed position in spaced relation to the top surface of the table 12. The arm 16 is thereby superimposed with respect to the arm 14, and coil springs 33 are adapted to be received between the arms 14 and 16. Such a spring is illustrated in its extended position by the full lines in Fig. 3. By moving the upper arm 16 downwardly to the position shown by the broken lines in Fig. 3, it will be understood that the spring 33 is compressed and is retained in its compressed condition between the arms 14 and 16.

Such downward movement of the upper arm 16 is effected through an air cylinder 34. The piston rod 28 extends downwardly through an aperture in the plate 24 and through an aperture in the table 12 and through the head end 36 of the cylinder 34. The inner end of the rod 28 is connected to a piston 38 which is disposed within the cylinder 34. A rubber sleeve 40 is disposed about the lower end of the rod 28 and above the piston 38 to serve as a bumper in limiting the upward movement of the piston 38 and the rod 28. An end closure 41 is fixed to the lower end of the cylinder 34 and is pivotally connected through a clevis 42 and pivot pin 44 with a frame member 45 of the table 10. Thus, the piston and cylinder assembly is mounted on the table support 10.

An air inlet and outlet port 46 is provided in the head 36 communicating with the upper end of the cylinder 34, and an air inlet and outlet port 48 is provided in the lower end 40 communicating with the lower end of the cylinder 34. Air conduits 50 and 52 are connected to the ports 46 and 48 respectively and lead to an operating control valve 54 which may be of conventional construction. A source of compressed air is supplied through the valve 54 by means of a conduit 56. Such valve 54 is actuated by a foot lever 58 which controls the flow of fluid through the valve and to either end of the cylinder 34. Thus, when fluid under pressure is supplied through port 46, the piston 38 is forced downwardly, depressing the rod 28 and drawing the arm 16 downwardly to compress the coil spring 33. The downward movement of the arm 16 is guided by the rods 20 and their cooperating guide sleeves 22.

A rubber sleeve 60 embraces the shaft 28 and is fixed to the plate 24. Such rubber sleeve 60 serves as a bumper against which the cross head 18 abuts when the arm 16 reaches the lower end of its stroke.

The spring 33 is engaged and guided during its compression by means of a guide gauge including a pair of upstanding rod members 62 which are adapted to engage the outer periphery of the coil spring 33 at spaced points therearound. Such rods 62 are mounted for vertical movement with the movement of the arm 16 and are also mounted for adjustment to accommodate springs of different diameters. The rods 62 extend through

elongated slots in the table 12 and also extend through complementary, elongated slots 64 formed in a mounting plate 66. The mounting plate 66 is secured to the underside of the table 5 12 by means of suitable bolts 68. In order to provide for the adjustment of the rod members 62 longitudinally of the slot 64, such rod members are received through apertures in a slidable plate member 70 to the underside of which tubular guide sleeves 72 are fixed in alignment with such apertures. The plate member 70 is provided with longitudinally extending flanges at its opposite side edges, which are adapted to be slidably mounted on guideways formed by elongated, L-shaped members 74, which are fixed to the plate members 76 at opposite side edges thereof.

The plate member 70 has a depending arm 76 fixed to the rear edge thereof, which is provided with a tapped opening 78 therethrough. Another depending arm 80 is fixed to a transverse plate member 82 adjacent the front edge thereof, and such plate member 82 is fixed with respect to the plate 66. The depending arms 76 and 80 are similar in shape and position with respect to each other, and the arm 80 is provided with an aperture therethrough which is aligned with the tapped opening 78. A crank rod 84 is disposed through the aperture in the arm 80 and has its inner end threaded, as indicated at 86. Such threaded end 86 is received within the tapped opening 78. It will thus be seen that by turning the crank shaft 84 the plate 70 is caused to move longitudinally of the guideways formed by the members 74 to thus move the rod 62 longitudinally of the aperture 64. In so moving the rods 62, it will be appreciated that the distance may be varied with respect to the longitudinal axis of the coil springs 33, so that such members may be positioned for different size springs.

The lower ends of the tubular guide members 72 may be connected by a cross head 88 having apertures therethrough, through which the rods 62 are slidably received so that the guides 72 are rigid for guiding the rods 62.

The lower ends of the rods 62 are welded to a plate member 90 which is provided with an elongated slot 92 adjacent the lower edge thereof.

The rod members 62 are caused to reciprocate with the arm 16 and the stroke of the rod 50 62 is greater than the stroke of the arm 16, so that the rod 62 will be moved downwardly to a position substantially flush with, or slightly below, the top surface of the table 12. In this way the rods 62 are moved to an out-of-the-way position so that the burlap strip may be slipped over the ends of the arms 14 and 16.

In order to give this movement to the rod member 62, an elongated lever 94 is provided, having one of its ends pivotally connected to the plate member 90 by means of a pivot pin 96 which is received within the slot 92. Such arm 94 is also pivotally connected to a cylindrical block member 98 by means of a pivot pin 100. Such block 98 is provided with a tapped pocket 102 in one end thereof, which is adapted to threadably receive the lower threaded end of one of the members 20 therein. Thus, the member 98 is fixed to this one of the rod members 20 and will reciprocate therewith upon actuation of the air cylinder 34.

Thus, as air is supplied to the upper end of the cylinder 34 to compress the arm 16, the rods 20 are moved downwardly. The rods 62 are correspondingly moved downwardly through the connection of the lever 94 with one of the rod

members 20, and with the plate member 90. As the arm 16 and the rods 62 approach their lower limits of movement, an additional or accelerated movement is provided the rods 62 to move them to the out-of-the-way position above mentioned. Such additional movement or increased stroke is provided by the opposite projecting end of the lever 94. Such opposite end has a curved element 104 fixed to the underside thereof, which is disposed above a bumper element 106 mounted to one of the frame members 108 of the support 10. As the lever 94 approaches its downward limit, it will be appreciated that the member 104 strikes the bumper 106 to pivot the lever 94 about the pivot 101. The pin 96 may thus move along the slot 92 and give the accelerated movement, or additional stroke, to the rod members 62 to move them to a position downwardly, substantially flush with, or slightly under, the top surface of the table 12.

A coil spring 110 is connected to the lever 94 between the pivot points 101 and 96, and extends upwardly, and has its opposite end connected to an upstanding bracket or plate member 112, the lower end of which is welded or otherwise suitably fixed to the member 98. Thus, the lever 94 is normally pulled in a clockwise direction about the pivot 101, viewing Fig. 3.

In the use of the device above described, the arm 16 is adjustably fixed on the piston rod 23 to accommodate the spring of any particular length. The rod members 62 are also adjusted, as above described, to accommodate the spring of any particular diameter. The spring is then positioned between the arms 14 and 16 as shown in Figs. 1, 3 and 4, and the air cylinder is then operated to depress the upper arm 16. The spring 33 is then compressed as shown by the broken lines in Fig. 3, and as diagrammatically illustrated in Fig. 8. At the completion of the downward stroke of the arm 16, the guide pins 62 have been moved to a position substantially flush with, or slightly below, the surface of the table 12.

Burlap strips 114 having elongated pockets defined by stitching 116, and having the lower ends closed by stitching 118, may then be positioned on the table 12 with the upper ends of the pockets directed toward the free ends of the arms 14 and 16. It will thus be appreciated that the springs 33 may be readily inserted into the pockets through the open ends thereof by slipping the free ends of such pockets over the free ends of the arms 14 and 16. A compressed spring is thus disposed in the bottom of the pocket, as shown in Fig. 9. After all of such pockets have been filled, the open ends thereof may be sewed shut by stitching 120, as shown in Fig. 10. Thereafter, the compressed springs may be turned through 90° from the position shown in Fig. 9 to that shown in Fig. 10, when they expand and fill the pockets of the burlap strips 114.

It will be appreciated that the operation of the apparatus of the present invention is quick, in that by depressing the pedal 58 the arm 16 is depressed, and remains depressed until the pedal 58 is released when the air is introduced into the upper or lower end of the cylinder 34 to raise the arm 16 together with the guide pins 62 to the

proper position for the reception of the next spring.

What is claimed is:

1. A device for handling coil springs comprising, a base, a standard on said base, spaced elements adapted to receive and compress a coil spring mounted above said base, means mounting said elements on said standard for movement relative to each other, movable guide means disposed adjacent to said elements for stabilizing the spring during its compression, and means for simultaneously moving said elements relative to each other and for moving said guide means.
- 5 2. A device for handling coil springs comprising, a base, a standard on said base, spaced elements adapted to receive and compress a coil spring mounted above said base on said standard, movable guide means disposed adjacent to said elements for stabilizing a spring during its compression, and means for simultaneously moving said elements relative to each other and for moving said guide means a greater distance than the distance of relative movement of said elements.
- 10 3. A device for handling coil springs comprising a support having a table portion, a pair of spaced, elongated elements disposed above said table portion and adapted to receive and compress a coil spring therebetween, means mounting said elements on said support in superimposed relationship with respect to each other and with the lower of said elements spaced from said table portion, elongated, movable guide means mounted on said standard and extending above said table adjacent to said elements, and means for moving the upper of said elements toward the lower of said elements to thereby compress a coil spring and for moving said guide means downwardly below the lower of said elements.
- 15 4. A device for handling coil springs comprising, a base, a standard on said base, spaced elements adapted to receive and compress a coil spring mounted on said standard above said base, a pair of movable rods disposed adjacent to said elements for stabilizing the spring during its compression, means for relatively adjusting said guide elements toward and from each other, and means for relatively moving said spaced elements toward each other while moving said guide elements therebelow.
- 20 5. A device for handling coil springs comprising a support having a table portion, a pair of spaced elongated elements disposed above said table portion and adapted to receive and compress a coil spring therebetween, means engaging one of the ends of each of said elongated elements and mounting such elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 25 6. A device for handling coil springs comprising, a base, a standard on said base, spaced elements adapted to receive and compress a coil spring mounted on said standard above said base, a pair of movable rods disposed adjacent to said elements for stabilizing the spring during its compression, means for relatively adjusting said guide elements toward and from each other, and means for relatively moving said spaced elements toward each other while moving said guide elements therebelow.
- 30 7. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 35 8. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 40 9. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 45 10. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 50 11. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 55 12. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 60 13. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.
- 65 14. A device for handling coil springs comprising, a support having a table portion, a pair of spaced elongated elements disposed above said table portion and adapted to receive and compress a coil spring therebetween, means mounting one of the ends of each of said elongated elements on said support in superimposed relationship with respect to each other and with the lower of said elements spaced from said table portion, stabilizing means extending above said table adjacent said elements, means for moving the upper of said elements toward and away from the lower of said elements to thereby compress a coil spring and for moving said stabilizing means downwardly to a position substantially flush with said table portion below the lower of said elements.

CLIFFORD F. PETERSON.
